Primary Examiner — Sheryl Lane*Assistant Examiner* — Ieisha N Price(74) *Attorney, Agent, or Firm* — LegalForce RAPC Worldwide(57) **CLAIM**

The ornamental design for a security screw, as shown and described.

DESCRIPTION

FIG. 1 is a front top perspective view of a security screw, showing our new design;

FIG. 2 is a front elevational view of thereof, with the rear elevational view, left side elevational view and right side elevational view being a mirror image of; and,

FIG. 3 is a top plan view of thereof.

The broken lines in the drawings illustrate portions of the security screw and form no part of the claimed design.

1 Claim, 3 Drawing Sheets(56)
